UNITED STATES PATENT OFFICE.

GEORGE E. LEE, OF CLEVELAND, OHIO, ASSIGNOR TO THE GEORGE E. LEE COMPANY, OF CLEVELAND, OHIO, A CORPORATION OF OHIO.

THERMOSTAT.

1,338,024.

Specification of Letters Patent. Patented Apr. 27, 1920.

Application filed May 10, 1915. Serial No. 27,007.

To all whom it may concern:

Be it known that I, GEORGE E. LEE, a citizen of the United States, residing at Cleveland, in the county of Cuyahoga and State of Ohio, have invented a certain new and useful Improvement in Thermostats, of which the following is a full, clear, and exact description.

This invention relates to thermostats, and the object of the invention is to provide a thermostat in which the flow of gas may be regulated so that the maximum amount of gas flowing may be regulated, and, further, to provide a thermostat in which the valve that regulates the flow of gas or fuel will be positively operated by the expanding and contracting members. Further objects of the invention will appear as the construction is described.

Generally speaking, the invention may be said to comprise the elements and combinations thereof set forth in the accompanying claims.

Reference should be had to the accompanying drawings forming a part of the specification, in which Figure 1 is a vertical section of a construction embodying a form of my invention; Fig. 2 is a vertical section of a thermostat embodying a modified form of my invention.

Thermostats at present in general use, of the type wherein movement is produced by differential expansion of metallic bars or members, provide that the valve be moved in one direction by the expanding member and in the opposite direction by a spring or other resilient means. There are certain forms of thermostats which employ a rubber or thin metal diaphragm which is operated by some expanding and contracting member, and in such case the return of the rubber or metal to its initial and original position is accomplished by the inherent resiliency of the material itself.

Continued use, as well as many other causes, may result in weakening the spring or in some way making it ineffective, so that the return of the controlling valve to its initial position is very slow and sometimes completely destroyed.

In the regulator which forms the subject matter of my invention I provide for the positive operation of the valve, which controls the flow of gas in both directions of movement of the valve, so that the valve is

positively operated under all conditions. Furthermore, I provide for the regulation of the flow of gas as to the maximum flow by an adjustment in the thermostat itself.

Referring to the drawings, and more particularly to Fig. 1 thereof, 1 indicates a casing, which, upon a side thereof, is provided with a neck 23, the interior of which is threaded and adapted to receive a pipe 24, this being the inlet pipe for the fluid fuel.

There is a hollow extending portion 4 which has an outwardly extending neck 5, the interior of the neck being threaded and adapted to receive a pipe 6, which pipe conveys the gas flowing out from the thermostat. The interior of the extending portion 4 is threaded and is adapted to receive a sleeve 7. This sleeve is hollow at least in part, and is adapted to extend into the chamber of the casing 1. The sleeve 7 closely engages the walls of the member 4 at the lower portion thereof, so as to provide a substantially gas-tight fit. The sleeve 7 is provided with openings indicated at 8, 80 by which gas flowing through the sleeve 7 may pass to the pipe 6. At its upper end the sleeve 7 is threaded and co-operated with threads upon the interior part of the extending portion 4. At its outer end sleeve 85 7 is provided with a head 7^a which is shaped to be conveniently engaged by a wrench. A lock nut 9 is adapted to lock the sleeve 7 with respect to the extending portion 4.

The casing 1 is provided with another neck 10, having the interior portion thereof threaded and adapted to receive a tubular member 11, which forms one element of the expanding and contracting elements of the thermostatic couple. The element 11 is 95 at its lower end closed and the rod 15 and element 11 are secured together at their lower end. The members 13 and 11 form elements of a thermostatic couple.

The bar 13 at its upper end is pivotally secured to a lever 14. This lever is fulcrumed intermediate of its ends. The lever 14 has a hub 15. Through this hub there extends a pin 16, the pin being journaled at its ends in the walls of casing 1.

It will be understood that the particular point in the lever 14, at which it is pivotally mounted, is chosen with regard to the sensitiveness desired in the instrument, that is to say, the distance between the fulcrum 110

point of the lever 14 and the point which it connects with the rod 13 will govern the sensitiveness of the device.

In the present construction I have departed somewhat from usual construction, in that the element 11 of the thermostatic couple is the member which has the higher coefficient of expansion, the member 13 being chosen to have a low co-efficient expansion. 10 I have, furthermore, departed from usual construction in that the element 13 of the thermostatic couple is fastened to the element 11. Therefore, as the element 11 elongates or contracts the element 13 must 15 take of the motion of the element 11 because it is fastened to it. It is clear that as the element 13 is moved it will move the lever 14 and the valve 19 positively in both directions of the movement of the valve. It will be 20 noted that the sleeve 7, the lower end of which forms the seat for valve 19, is removable. The sleeve may be moved to permit inspection, or for purposes of cleaning the lower end of the sleeve which serves as a 25 valve seat, and this without disturbing the other elements of the thermostat.

For purposes of assembling the elements of the device the casing 1 has an opening at one end which is normally closed by a 30 cover 22.

The lever 14 has secured thereto a spring 25. This spring, at its outer end, carries a head 26. This head is provided with an opening through which opening extends a 35 short post 27. The post 27 is provided with a slot 28 and through the slot there extends a pin 29, which pin is secured in the head 26. The post 27 carries the valve 30, this valve being adapted to engage the lower end of 40 the sleeve 7. Between the head 26 and the valve 30, and surrounding the post 27, is a spring 31 which normally urges the valve away from the head 26 so that the pin 29 is usually in the lowest part of the slot 28. 45 The lower end of the post 27 is in line with a threaded stop member 32. This stop member 32 extends through a threaded opening in the casing and engages the lower end of the post 27. The member 32 is provided 50 with a lock nut 33 which holds the member 32 in adjusted position.

In the operation of the device shown in Fig. 1 the downward movement of the valve 30 is limited by the engagement of the post 55 27 with the stop member 32.

It will be seen that this construction provides a means of adjustment to regulate the maximum amount of gas passing into the burner. Or, perhaps it may be more accurate to say that this adjustment presents a means of regulating the size of the opening between the valve 30 and its seat, which opening governs the quantity of gas supplied to the pipe 6.

65 In Fig. 2 I have shown a form of thermo-

stat which in part is similar to the form shown in Fig. 1, that is to say, the casing with its co-operating parts is quite the same as are also the elements forming the thermostatic couple. The valve mechanism, however, 70 differs from that shown in Fig. 1.

In this construction I have provided a self-contained valve mechanism which may be removed as an entirety from the thermostat for purposes of inspection, repairs or 75 cleaning.

The extending portion 4 receives a sleeve 35. This sleeve is threaded at its upper end and is received into the threaded end of the portion 4. A lock nut 36 will lock the sleeve 35 in adjusted position. This sleeve is provided with openings 37 for the purpose of permitting the passage of fuel from the interior sleeve to the exit pipe 6.

Extending through the upper part of the 85 sleeve 35, and centrally of the hollow portion of the sleeve, is a threaded rod 38. This stem has a threaded engagement with the upper part of the sleeve 35 and may be adjusted longitudinally with respect to the 90 sleeve 35.

Adjacent to its lower end the rod 38 is provided with a slot 39, which slot is adapted to receive a transverse pin 40. The pin is carried by a valve stem 41 which at 95 its lower part is secured to a valve 42. The rod 38 is counter-bored at its lower end to receive the stem 41. There is a spring 43 which surrounds the stem 41 and at its opposite ends engages with the valve 42 and 100 the lower part of the rod 38, normally holding the valve 42 in its lowest position. The lower portion of the sleeve 35 is so formed as to co-operate with the valve 42, forming a 105 gas-tight seal when the valve is in engagement with the lower part of the sleeve 35.

The valve 42 is operatively engaged by an operating element 44. This element is provided with a certain amount of flexibility for purposes which have heretofore been described in connection with the other constructions shown in the drawing. The element 44 is secured to the end of the lever 14, which lever is operated by the thermostatic couple in the same manner as has heretofore 115 been described.

It will be seen that by moving the stem 38 it will be possible to regulate the maximum opening between the valve 42 and the end of the sleeve 35, thus permitting an adjustment to regulate the maximum quantity of gas which may flow. The operation of the valve 42 by the thermostatic couple is not interfered with, for the valve 42 may move upward against the action of the 125 spring 43 when the lever 45 and the element 44 are moved.

The sleeve 35 is removable together with the valve and its operating mechanism as a unit, so that the valve and its valve seat may 130

be inspected, repaired or cleaned, without in any way interfering with the mechanism of the thermostat.

Having thus described my invention, what

5 I claim is:—

1. A thermostatic device comprising a casing having an inlet and an outlet, and a valve seat within said casing, a valve co-operating with said seat, means for adjusting 10 the said valve seat and valve with respect to each other independent of the thermostatic couple thereby to control the maximum opening between the valve and its seat, a thermostatic couple carried by the casing 15 and operative connections between the thermostatic couple and the valve.

2. A thermostatic device comprising a casing having an inlet and outlet, a valve seat within said casing, a valve co-operating with 20 said valve seat, means for adjusting the valve and its seat relative to each other independent of the thermostatic couple thereby to control the maximum opening between the valve and its seat, a lever mechanism 25 within the casing, said lever mechanism being operatively connected with the valve, a thermostatic couple mounted upon the casing between said thermostatic couple and the lever mechanism.

30 3. A thermostatic device comprising a cas-

ing having an inlet and outlet opening, a sleeve extending into said casing, a valve co-operating with said sleeve, means for relatively adjusting the sleeve and valve independent of the thermostatic couple, thereby 35 to regulate the maximum opening between the valve and sleeve, a thermostatic couple and means operatively connecting the thermostatic couple with the valve.

4. A thermostatic device comprising a casing having an inlet and outlet opening, a sleeve extending into said casing and adjustable with respect to the casing, a valve associated with the inner end of the sleeve, 40 means for relatively adjusting the valve and the sleeve independent of the thermostatic couple, thereby to regulate the maximum opening between the valve and the sleeve, lever mechanism within the casing, a thermostatic couple carried by the casing, connections 45 between the thermostatic couple and the lever mechanism, and connections between the lever mechanism and the valve.

In testimony whereof, I hereunto affix my 50 signature in the presence of two witnesses. 55

GEORGE E. LEE.
